HIGHWAY GUARD

Robert H. Irons, Harrisburg, and Alexius E. Eck,
Camp Hill, Pa., assignors to Central Iron &
Steel Company, Harrisburg, Pa., a corporation
of Pennsylvania

Application December 11, 1934, Serial No. 757,032

6 Claims. (Cl. 256—13.1)

This invention relates to improvements in highway guards, and more particularly to that type of guard in which the rail is formed of elongated steel plates.

5 One object of the invention is to provide a guard of this type that shall be characterized by extreme simplicity of construction and simplicity of manufacture and assembly.

A more specific object of the invention is to 10 provide a resilient bumper element for highway guards of the stated type including novel and improved means for supporting the rail elements.

Still another object of the invention is to provide novel means for resiliently supporting the 15 rail element so that it may have freedom of longitudinal movement with respect to the resilient rail-supporting elements.

The invention further resides in certain novel structural features hereinafter described and illustrated in the attached drawing, in which:

20 Figure 1 is a plan view of a guard made in accordance with our invention;

Fig. 2 is a front elevation of the guard assembly shown in Fig. 1;

Fig. 3 is a fragmentary perspective view showing details of the construction;

Fig. 4 is a section on the line 4—4, Fig. 1;

Fig. 5 is a fragmentary view in perspective illustrating further details of the construction; and

30 Fig. 6 is a view in perspective illustrating a modification within the scope of the invention.

With reference to the drawing, a highway guard made in accordance with our invention comprises a series of spaced main supports 1 illustrated in the present instance as upright posts which may be of wood or any desired material. To the side of each of the intermediate supports 1 is attached a resilient bumper element 2, to which is attached the rail 3. The bumpers 2 take the form in the illustrated embodiment of sheet metal loops, the overlapped free ends of which are secured against the supports 1 by means in the present instance of bolts 4. These bolts preferably pass completely through the posts which constitute the main supports. Where as in the present instance, the posts are made of wood, it is preferred to insert between the posts and the bumpers a suitable washer plate 5. Preferably and as illustrated, the forward or outer faces of the bumpers 2 are convexed or curved in the transverse direction.

In accordance with our invention and in the preferred embodiment, each of the bumpers 2 is provided on its forward face with an integral pressed-out flat loop 6, through which are passed

the plate elements of the rail 3. Preferably the said plates are left free to slide longitudinally through the supporting loops 6, although following assembly and if desired, the plates may be fixed in the loops by suitable means without departure from the invention. Intermediate the supports 1, the plates which constitute the rail 3 are secured together in any suitable manner as by means of bolts 7.

The rail 3 is secured to the terminal supports 1 of the series by means illustrated in Figs. 1, 2, and 5. To each end of the rail proper is secured a pair of straps 8, 8 which together with transverse flanged plates 9 and 10 form an open box structure into the end of which is passed one or 15 more retaining bolts 11. The inner ends of these bolts which pass through apertures in the plate 9 are threaded for reception of nuts 12 which engage the ends of coiled springs 13 on the bolts, the other ends of the springs engaging the plate 10. The bolts 11, as shown in Fig. 2, extend through the end posts 1 and may be tightened to place the rail 3 under tension by turning the bolts from the outer ends, the springs 13 under tension acting to hold the nuts 12 stationary during 20 the tightening operation. Tensioning the rail 3 is effected through the springs 13 which accordingly act as resilient retainers for the rail. The terminal posts 1 are supported against the weight and tension of the rail by suitable anchored tension rods 14.

One of the principal advantages of the construction resides in its extreme simplicity of form, manufacture and assembly. In assembling the structure, the bumper elements 2 may first 35 be secured to the respective posts, after which the individual rail plates are passed endwise through the strap 6; or the rail elements may be assembled with the respective bumper elements prior to securing the latter elements to the posts. 40 The ends of the rail plates may then be secured together by the bolts 7, after which the bolts 11 and nuts 12 are manipulated to place the assembled rail under tension.

A desirable feature of the structure resides in 45 the fact that the main supports 1 do not require absolutely accurate spacing as in many of the prior types of highway guard. The use of the integral strap 6 of the bumper elements 2 avoids the necessity for separate and more complicated means for attaching the rail 3 to the bumper elements. Also this construction permits longitudinal adjustment of the rail 3 with respect to the individual bumpers so that excessive strain is 50 55

never concentrated on any one of the last-named elements.

It will be apparent that there may be some modification in the structure as described above 5 without departure from the invention. Instead for example of using the continuous strap 6 for supporting the rail on the bumper elements, the said elements may be provided as shown in Fig. 6 with pressed-out lugs 15, 16 arranged to embrace 10 the opposite longitudinal edges of the rail. In this latter type of construction, it is possible to form one or both of the lugs 15 originally so that they project outwardly at right angles to the bumper surface and to bend these lugs or cleats 15 over the edge of the rail after the latter has been positioned against the face of the bumper. It is preferred, however, to form the lugs 15 originally as illustrated in Fig. 6, so that the rail may have 20 relative freedom for longitudinal sliding movement and so that there may be no tendency for these elements to bind the rail at the points of application.

We claim:

1. As a new article of manufacture, a resilient 25 sheet metal bumper for highway guard rails comprising integral pressed-out rail-supporting means formed to embrace both longitudinal edges of the rail.
2. As a new article of manufacture, an inherently resilient sheet metal element constituting 30

a carrier for a highway guard rail and comprising integral means for slidably supporting the rail thereon, said element being adapted to be secured to a supporting member and to form a resilient bumper between said member and the 5 rail.

3. As a new article of manufacture, a resilient sheet metal bumper for highway guard rails having an integral pressed-out rail-embracing strap.

4. As a new article of manufacture, a resilient 10 sheet metal bumper for highway guard rails having integral pressed-out clips adapted to embrace the opposite longitudinal edges of said rail.

5. A highway guard comprising in combination, a main support, a sheet metal bumper carried by said support, said bumper having a portion thereof pressed out to form a flat loop, and a sheet metal rail passing freely through said loop and supported thereby on the bumper. 15

6. A highway guard comprising in combination, a main support, a sheet metal bumper in the form of a loop secured to and projecting transversely from the support, the forward face of said bumper being convexed in the transverse direction, a sheet metal rail positioned against 25 said face, and an integral element pressed out of the metal of said bumper and loosely engaging and supporting said rail. 20
